UNITED STATES PATENT OFFICE.

EDD DOZIER, OF VERSAILLES, KENTUCKY, ASSIGNOR OF ONE-HALF TO CARL H. LEDENDECKER, OF VERSAILLES, KENTUCKY.

LOCKING DEVICE FOR RAILROAD-TRACK JOINTS.

Application filed November 25, 1925. Serial No. 71,356.

To all whom it may concern:

Be it known that EDD DOZIER, a citizen of the United States of America, residing at Versailles, State of Kentucky, county of 5 Woodford, has invented an Improved Locking Device for Railroad-Track Joints, of which the following is a specification.

The present invention has for its purpose to provide in a railroad track joint, an improved locking device for the nuts on the bolts, which pass through the adjoining ends of the rails and the fish plates, the locking device being such that it can be applied to all 10 joints, and more especially to those occurring 15 immediately adjacent the frog of a switch. In other words, the switch rail and the main rail extend at an angle to each other, a frog being used to hold them in position, and most locking devices of this 20 character are incapable of being inserted downwardly between the two rails. To apply such locking devices, they have to be moved laterally to engage with the nuts. However, in the present construction the 25 locking device can be dropped or inserted vertically down between the rails and easily engaged with the nuts and then secured 30 in position.

It is to be understood that the particulars 35 herein given are in no way limitative and that while still keeping within the scope of the invention, any desired modifications of the detail and desired proportions may be made in the apparatus according to the circumstances.

The invention comprises further features and combination of parts, as will be herein-after set forth, shown in the drawings and claimed.

40 In the drawings:

Figure 1 is a view in perspective of a railroad track joint, showing the improved locking device applied and constructed in accordance with the invention.

45 Figure 2 is a longitudinal sectional view on line 2-2 of Figure 1.

Figure 3 is a transverse sectional view on the line 3-3 of Figure 1.

50 Figure 4 is a detailed perspective view of one of the plates which is carried by certain of the bolts of the joint.

Figure 5 is a detailed perspective view of one end of the locking device.

55 Figure 6 is a detail perspective view of one of the washers 14.

Referring to the drawings, 1 and 2 designate the joining end portions of two rails, the adjacent extremities of which define a conventional joint. Opposed fish plates 3 and 4 are provided. These fish plates conform to and fit the webs of the rails, the bases 5 of the fish plates also conforming to and fitting the opposite portions of the rail bases, while the vertical parts of the fish plates fit between the under portions of the 60 balls of the rails and the bases thereof.

Conventional bolts 6 pass through the fish plates and through the webs of the rails. These bolts have rectangular portions 7 immediately adjacent their heads 8, said 70 rectangular portions fitting within correspondingly shaped openings 9 of the fish plate 4, there being suitable washers 10 between the heads 8 and the face of the fish plate 4. By this construction the bolts are 75 prevented from turning. It is to be noted that the openings 9 are elongated, that is to say, in a horizontal direction, in order to prevent binding and to allow movement of the fish plates due to expansion and contraction. The cylindrical portions of the bolts 6 pass through elongated openings 11 and 80 12 of the webs and the fish plate 3, such elongated openings also allowing the rails and the fish plate 3 relative movement due 85 to expansion and contraction.

The usual nuts 13 are threaded upon the ends of the bolts 6, and between them and the fish plate 3 suitable washers 14 are applied. These washers are of the spring split 90 type, the split ends thereof being sprung laterally, offering resistance to the nuts 13 as they are applied to the bolts, thereby insuring a secure, close and tight fit of the nuts on the bolts, and furthermore, to insure a constant clamped action between the 95 several elements of the railroad joint.

There have been different locking devices to prevent the nuts 13 from backing off, but those which may have any bearing on this 100 construction are so designed that it is necessary to apply them by lateral movements, that is, in a horizontal direction to cause them to engage with the nuts. Obviously, locking devices so applied cannot be used 105 in connection with railroad track joints immediately adjacent a frog of a switch. That is, where a switch rail is disposed at a very slight angle to the main rail. It is impractical to insert the locking device downward- 110

ly into the crotch between the switch rail and the main rail, so that the locking device can be moved laterally in a horizontal direction. However, with the present locking device it is possible to insert the locking element 15 vertically downwardly between the switch rail and the main rail immediately adjacent the apex of the crotch, or rather in the V caused to be formed by disposing the switch rail at a slight angle to the main rail. In inserting the locking element or device 15 in this manner, its notches 16 straddle the nuts, and, obviously, when the locking element is secured, the nuts are prevented from turning or backing off.

To hold the locking element or device in position engaged with the nuts, plates 17 are provided. These plates have elongated openings 18, which receive certain of the bolts of the joint, that is, the end bolts, said plates 17 being interposed between the spring split washers 14 and the face of the fish plate 3. Where the openings 18 are formed, the plates 17 have extension ears 19. The plates 17 also have lateral ears 20, which are provided with slightly elongated openings 21. After applying the plates 17 in position, the nuts 13 are secured upon the bolts, but not entirely home. Consequently, the plates 17 are loose. The locking device or element is then temporarily applied to the nuts 13, and as the notches 16 are in the act of straddling the nuts, the inclined edges 22 at the opposite ends of the locking device or element wedge against the edges of the lateral ears 20, thereby causing the plates 17 to adjust themselves in their proper positions. The locking device or element is then removed for the time being and the nuts 13 are then turned home, that is, tightened and adjusted to the position shown in Figure 1. The locking element is again applied, and this time permanently, in which case the end projections 23, (which extend downwardly) of the locking element enter the elongated openings 21 of the ears 20 of the plate 17. The lower portions of the projections 23 have openings for the reception of cotter keys or pins 24, thereby holding the locking element securely connected to the lateral means of the plates 17, and hence, preventing any derangement of the various parts. Obviously, the nuts 13 are prevented from backing off, and at all times rendering the railroad track joint secure. The usual spikes 25 are used to engage the bases of the fish plates in order to secure the rails to the

ties, (not shown). The plates 17 are so disposed that their lower edges 26 rest upon the upper surfaces of the bases of the fish plates, thereby preventing any turning movement of the plates.

The invention having been set forth what is claimed is:—

1. In a locking device for railroad track joints, the combination with adjoining end portions of a pair of rails including fish plates positioned in contact with the webs of the rails with bolts passing through said parts and nuts thereon to hold them together, of plates mounted upon the end bolts and provided with lateral ears, and a locking element with notches applicable to the nuts in a vertical direction parallel with one of the fish plates and having downwardly extending end projections passing through the ears, and provided with means to hold them in position and preventing upward movement of the element.

2. In a locking device for a railroad track joint, the combination with adjoining end portions of a pair of rails, including fish plates, and bolts passing through the fish plates and the rails with nuts thereon, of plates initially loose upon the end bolts and provided with lateral ears, a locking element comprising an elongated bar with notches applicable in a vertical direction parallel with one of the fish plates, whereby the notches may straddle the nuts temporarily, said bar having inclined edges to cooperate with the ears, to adjust the plates in their proper positions.

3. In a locking device for a railroad track joint, the combination with adjoining end portions of a pair of rails, including fish plates, and bolts passing through the fish plates and the rails with nuts thereon, of plates initially loose upon the end bolts and provided with lateral ears, a locking element comprising an elongated bar with notches applicable in a vertical direction parallel with one of the fish plates, whereby the notches may straddle the nuts temporarily, said bar having inclined edges to cooperate with the ears, to adjust the plates in their proper positions, said bar having downwardly extending end projections to pass through the ears when applying the bar, and means passing through the lower ends of the projections to prevent upward movement of the bar.

In witness whereof, the inventor's signature is hereunto affixed.

EDD DOZIER.
